UNITED STATES PATENT OFFICE.

CLARENCE D. BAIRD, OF ALEXANDRIA, TENNESSEE, ASSIGNOR OF ONE-FOURTH TO
I. A. EATON, OF ALEXANDRIA, TENNESSEE.

FEED-REGULATOR FOR GAS-GENERATORS.

1,277,823.

Specification of Letters Patent. Patented Sept. 3, 1918.

Original application filed June 30, 1917, Serial No. 177,920. Divided and this application filed June 4, 1918.
Serial No. 238,236.

To all whom it may concern:

Be it known that I, CLARENCE D. BAIRD, a citizen of the United States, residing at Alexandria, in the county of Dekalb and 5 State of Tennessee, have invented certain new and useful Improvements in Feed-Regulators for Gas-Generators, of which the following is a specification.

This invention relates to acetylene gas 10 generators and more particularly to an improved means for regulating the feed of carbid to the generating chamber, and this application is a division of my copending application filed June 30, 1917, Serial No. 15 177,920.

As is usual in apparatus of this class, the generator of the present invention includes a gas bell into which the generated gas is discharged and from which it is conducted 20 to the burners and the object of the present invention is to provide means actuated through the lowering movement of the gas bell for automatically opening the valve which controls the discharge of carbid from 25 the carbid hopper into the generating chamber so that the apparatus will be entirely automatic in its operation.

Another object of the invention is to provide means whereby the distance to which 30 the valve is opened may be regulated so as to thereby regulate the quantity of carbid discharged at any one time and which means will be located exteriorly of the generator so as to permit of ready accomplishment of 35 the desired adjustment without interrupting the operation of the generator.

In the accompanying drawings:

Figure 1 is a perspective view of a gas 40 generator embodying the present invention; Fig. 2 is a vertical sectional view through the generator, the elements of the regulating device being shown in elevation as also the carbid hopper;

Fig. 3 is a view similar to Fig. 2 but illustrating a slight modification of the invention and showing also the hopper and valve in vertical section.

In the drawings the generating chamber 50 is indicated by the numeral 1 and the collecting and storage device is arranged beside the said generating chamber 1 and includes a tank indicated by the numeral 2, which in that form of the invention shown in Figs. 1 and 2 of the drawings is spaced from the

generating chamber 1, but in the form shown 55 in Fig. 3 is either an integral part thereof or placed immediately beside the said generating chamber. The gas bell is indicated by the numeral 3 and the lower open end of this bell is, as is usual, immersed in water 60 in the tank 2, the tank being open at its upper end. Gas generated within the chamber 1 is conducted through one or more pipes 4 from the said chamber to a collecting chamber indicated by the numeral 5 and 65 located at the bottom of the tank 2, as shown in Fig. 2 of the drawings, or this pipe 4 may lead into the upper end of an annular gas collecting chamber as shown in Fig. 1. Such a collecting chamber is shown in Fig. 3 of 70 the drawings and is indicated by the numeral 5, and whether one form or another of collecting chamber be employed, a conducting pipe 6 leads from the collecting chamber up into the bell 3 so as to discharge 75 the generated gas into the said bell. An outlet pipe 7 leads, of course, from the bell to the supply main from which the gas is finally conducted to the burners. Of course, if the gas is not being consumed, the bell 3 80 will be elevated as the generated gas collects therein and on the other hand as the gas is consumed and the volume within the gas bell decreases, the bell will, of course, lower. The numeral 8 indicates the carbid 85 hopper and 9 the valve which controls the supply of carbid from the hopper into the generating chamber 1. The valve 9 is provided with a stem 10 which fits slidably within a tubular guide 11 located centrally 90 within the hopper 8, and the upper end of this stem projects exteriorly of the said hopper.

The device embodying the present invention is designed to provide for downward 95 movement of the valve 9 to permit carbid to flow into the generating chamber when the gas bell 3 has lowered to a predetermined point. The device includes a supporting arm which is indicated by the numeral 12 100 and which extends laterally from the top of the carbid hopper, and which arm supports pulleys indicated one by the numeral 13 and the other by the numeral 14. A cable 15 is trained over these pulleys and at one end is 105 connected to a swivel 16 upon the upper end of the gas bell 3. After passing over the pulley 13, the cable is led downwardly

through an opening 17 formed in the said supporting arm 12 and is connected at its other end to a counterweight 18 which balances or nearly balances the weight of the bell 3. The supporting arm 12 is held upon the top of the carbide hopper by means of the base 19 of an upstanding bracket 20 upon which is supported for oscillatory movement a rock arm 21. Pivotedly connected to one 10 end of this arm is a rod 22 which extends downwardly through the opening 17 and which is provided at its lower end with a horizontally disposed eye, indicated by the numeral 23, and through which the cable 15 passes. Adjustably arranged upon the cable 15 is an abutment 24 clamped in any suitable manner to the said cable and located below the eye 23. A weight 25 is fixed upon the rod 22 and counterbalances or substantially counterbalances the weight of the valve 9. The upper end of the valve stem 10 is provided with a transverse pin 26 which at its ends works in slots 27 formed in the spaced portions of the arm 21, the said arm 20 being preferably formed from a suitable length of bar metal bent upon itself midway of its ends to provide the said spaced portions.

From the foregoing description of the invention it will be understood that as the gas 30 is consumed and its generation in the chamber 1 slackens, the bell 3 will lower carrying with it the stretch of the cable 15 which is connected with the bell. As a result the abutment 24 will engage the eye 23 whereupon the rod 22 will be raised thus rocking the arm 21 and causing lowering of the valve stem 10 and opening of the valve 9 to admit a charge of carbide through the generating 35 chamber. Of course, the abutment 24 may be adjusted upon the cable 15 so as to cause opening of the valve when the bell 3 has descended to any predetermined position.

In both forms of the invention the abutment 45 is located exteriorly of the generating chamber and may, therefore, be conveniently adjusted upon the cable and in that form of the invention shown in Figs. 1 and 2 of the drawings, the weight 18 is suspended between the generating chamber and the tank 50. In the form shown in Fig. 3, however, a tubular casing 28 is arranged within the generating chamber and opens at its upper end through the top of the said chamber, and the weight and the stretch of the cable which is connected to it are housed in this casing.

Having thus described the invention, what is claimed as new is:

1. In a gas generator of the class described, a generating chamber, a carbide hopper arranged to discharge into said chamber, a valve for controlling the discharge of carbide from the hopper, a stem extending from the valve, a rocker arm having connection 60 with the said stem, an abutment member

connected with the arm at the other side of the pivot therefor, a gas bell arranged to receive the gas generated within the generating chamber, a flexible element connected with the gas bell, and an abutment element 70 carried by the said flexible element and arranged for coaction with the abutment member which is connected with the rocker element.

2. In a gas generator of the class described, a generating chamber, a carbide hopper arranged to discharge into said chamber, a valve for controlling the discharge of carbide from the hopper, the said valve having a stem extending exteriorly of the 80 hopper, a rock arm having pivotal connection with the valve stem, a pulley located adjacent the said rock arm, a gas bell arranged to receive the gas generated within the said chamber, a flexible cable connected with the bell and passing over the said pulley, a weight carried by the cable, and coacting abutment elements upon the rock arm and cable.

3. In a gas generator of the class described, a generating chamber, a carbide hopper arranged to discharge into said chamber, a valve for controlling the discharge of carbide from the hopper, the said valve having a stem extending exteriorly of the hopper, a 90 rock arm having pivotal connection with the valve stem, a pulley located adjacent to the said rock arm, a gas bell arranged to receive the gas generated within the said chamber, a flexible cable connected with the bell and passing over the said pulley, a weight carried by the cable, an abutment element connected with the rock arm, and an abutment element 95 adjustably carried upon the cable and arranged for coaction with the first- 100 mentioned abutment element.

4. In a gas generator of the class described, a generating chamber, a carbide hopper arranged to discharge into said chamber, a valve for controlling the discharge of carbide from the hopper, the said valve having a stem extending exteriorly of the hopper, a rock arm having pivotal connection with the valve stem, a pulley located adjacent the 110 said rock arm, a gas bell arranged to receive the gas generated within the said chamber, a flexible cable connected with the bell and passing over the said pulley, a weight carried by the cable, a rod pivotally connected with the rock arm and having an eye slidably receiving the cable, and an abutment member carried by the cable and moving in the path of the said eye.

5. In a gas generator of the class described, a generating chamber, a carbide hopper arranged to discharge into said chamber, a valve for controlling the discharge of carbide from the hopper, the said valve having a 125 stem extending exteriorly of the hopper, a rock arm having pivotal connection with the

valve stem, a pulley located adjacent the said rock arm, a gas bell arranged to receive the gas generated within the said chamber, a flexible cable connected with the bell and passing over the said pulley, a weight carried by the cable, a rod pivotally connected with the rock arm and having an eye slid-

ably receiving the cable, an abutment member carried by the cable and moving in the path of the said eye, and a counterweight 10 carried by the said rod.

In testimony whereof I affix my signature.

CLARENCE D. BAIRD.
